(57) **CLAIM**

We claim the ornamental design for an artificial log, as shown and described.

DESCRIPTION

FIG. 1 is a perspective view of the artificial log.

FIG. 2 is a right-side view of the artificial log.

FIG. 3 is a top view of the artificial log.

FIG. 4 is a front view of the artificial log.

FIG. 5 is a rear view of the artificial log.

FIG. 6 is a left-side view of the artificial log.

FIG. 7 is a bottom view of the artificial log; and,

FIG. 8 is cross-sectional view of the artificial log of FIGS.

1-7 magnified to illustrate surface features that protrude outwardly from an exterior surface of the artificial log. The surface features are in broken lines in FIGS. 1-8.

The broken line showing of the artificial log is for the purpose of illustrating portions of the article and forms no part of the claimed design.
